(57) **CLAIM**

We claim the ornamental design for a hazardous condition detector, substantially as shown and described.

DESCRIPTION

FIG. 1 is a perspective view of a hazardous condition detector;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of structural features is included for the purpose of illustrating non-claimed subject matter and forms no part of the claimed design.
